MICROMANOMETER

William S. Young, Philadelphia, Pa., assignor to
 The Atlantic Refining Company, Philadelphia,
 Pa., a corporation of Pennsylvania

Application May 11, 1946, Serial No. 669,040

10 Claims. (Cl. 73—401)

1
 The invention relates to improvements in devices adapted for the measurement of low pressures, and more particularly for the measurement of small changes in pressures at very low pressures.

In the ordinary manometer designed to measure pressures at substantially atmospheric pressure, mercury can be utilized satisfactorily due to its density, inertness, and non-volatility. However, in a micromanometer adapted for the measurement of extremely low pressures with a high degree of accuracy, for example .1 micron accuracy at 10 microns pressure, the use of mercury alone has been found to be impractical. As a result of its great density and high surface tension, mercury will not react to small changes in pressure in such a way as to permit sufficiently accurate measurements. In such a situation, liquids having low density and surface tension have been found to be eminently satisfactory except that such liquids are, as a rule, volatile at low pressures and, as a result, tend to dissipate. Such being the case, the partial pressure of the liquid will affect the pressure of a gas sample being measured, and will also tend to adulterate such sample.

One of the objects of the invention, therefore, is to provide a micromanometer which will accurately measure low pressures or changes in pressure at relatively low pressures.

Another object of the invention is to provide a micromanometer in which liquids having a low density and surface tension can be used without volatilization thereof.

Other objects of the invention will be apparent from the description and claims which follow.

In the drawing like numerals are used to designate like parts.

The figure shows a front elevational view of the device which is shown as fabricated of glass.

In the drawing, 1 and 2 are vertically arranged U-tubes preferably having a length between 700 and 760 mm. Affixed to the ends of the shorter arms of said tubes are lower reservoirs 3 and 4 respectively, the diameter of said lower reservoirs being relatively larger than the diameter of said tubes. Capillary tube 5 connects the upper portions of said lower reservoirs.

Inlet tube 6 is connected to capillary tube 5 and controlled by three-way stopcock 7, such stopcock providing controllable means of communication with supply reservoir 8 and air inlet 9, the latter being controlled by stopcock 10.

Upper reservoirs 11 and 12 are affixed to the

2
 ends of the longer arms of U-tubes 1 and 2 respectively, the diameter of said upper reservoirs being relatively larger than the diameter of said tubes. Said upper reservoirs are provided with elongated necks 13 and 14 respectively, to which are attached stopcocks 15 and 16 respectively. These stopcocks are of the hollow plug variety, the plug walls 17 and 18 respectively being apertured at 19 and 20 respectively, and the bottom of the plugs being open to provide communication with elongated necks 13 and 14 respectively. Stopcock 15 is provided with side arm 21 through which connection is made with a vessel, the pressure of whose contents it is desired to measure. Affixed to neck 13 is inlet tube 22 through which mercury can be introduced into the micromanometer, as will be described in detail hereinafter. Horizontal tube 23 affords communication between neck 13 of upper reservoir 11 and stopcock 16 affixed to neck 14 of upper reservoir 12.

In preparing the micromanometer for operation, stopcocks 15 and 16 are opened and stopcocks 7 and 10 are closed. The micromanometer is then evacuated by connecting stopcock side arm 21 to a suitable vacuum pump, such as a mechanical pump or a mercury vapor pump (not shown). In order to remove air adsorbed on the walls of the device, such walls may be heated with a flame or a hot air gun, precautions being taken to protect the various stopcocks. Stopcocks 15 and 16 are then closed ensuring a continued vacuum within the device. Mercury is distilled into the micromanometer through inlet tube 22 until the level of the mercury is approximately even with the bottom of the upper reservoirs and inlet tube 22 is sealed off as at 24, for example by the application of flame.

A suitable liquid, which has been thoroughly degassed, is admitted through stopcock 7 from supply reservoir 8 into capillary tube 5 until the interface between the mercury and the liquid stands approximately halfway up the vertical sides of lower reservoirs 3 and 4. The suitability of the liquid for such purpose consists in its low density and surface tension and its ability to contact mercury and yet remain unreacted. The specific liquid used here is normal pentane, but any liquid conforming to the aforementioned requirements can be used. As a result of the admission of liquid and the consequent displacement of mercury in the lower reservoirs, the meniscus of mercury in the upper reservoirs will stand approximately halfway up the vertical sides of said upper reservoirs.

A bubble of air 25 or any other suitable gas which will not react with the liquid used is introduced into capillary tube 5 by means of air inlet 9, stopcock 10, and stopcock 7. The position of such bubble can be adjusted in relation to a small scale (not shown) associated with said capillary tube by the addition or withdrawal of liquid. It will readily be understood that, if so desired, the scale itself can be moved in relation to the bubble.

The operation of the device is as follows:

When it is desired to measure the pressure of a gas, side arm 21 of stopcock 15 is connected with a vessel containing the gas. Stopcock 15 is then opened and communication is made between neck 13 of upper reservoir 11 and the vessel containing the gas. The resulting increase in pressure on the surface of the mercury in upper reservoir 11 results in a downward displacement of the mercury in U-tube 1 and a consequent lateral displacement of the bubble positioned in capillary tube 5. From the linear displacement of the bubble, the known dimensions of the reservoirs and capillary tube, and the density of the mercury and the other liquid used, the actuating pressure can be calculated as follows:

$$\text{Sensitivity } S = \frac{l}{P}$$

Where l is the bubble displacement in mm. and P is the applied pressure in mm. of mercury.

Setting up a datum plane at A-A in the figure, and dividing the micromanometer into two halves by B-B, the left half being denoted by subscripts 1 and the right half by subscripts 2, the micromanometer at equilibrium after evacuation satisfies the following relation:

$$(1) P_1^o + (H_1\rho_m - h_1\rho_p) = P_2^o + (H_2\rho_m - h_2\rho_p)$$

where P^o is the residual pressure acting on the upper reservoirs after evacuation.

H is the head of the mercury above the datum plane

h is the head of pentane above the datum plane
 ρ_m is the density of mercury

ρ_p is the density of n-pentane, all in consistent units.

Let an unknown pressure P be applied to the left hand reservoir, then

$$(2) P + (P_1^o + H_1\rho_m - h_1\rho_p) - 2\Delta H\rho_m + \Delta H\rho_p = \Delta p + (P_2^o + H_2\rho_m - h_2\rho_p) + 2\Delta H\rho_m - \Delta H\rho_p$$

where the change in mercury and pentane heads in each reservoir is identical and equal to ΔH , and the change in pressure in the right hand reference reservoir, due to compression caused by the head change is equal to Δp .

Subtracting 1 from 2 and solving for the applied pressure,

$$(3) P = \Delta p + 2\Delta H \left(2 - \frac{\rho_p}{\rho_m} \right)$$

Assuming incompressible fluids, the volume transferred from the reservoirs due to the change in head must equal the volume transferred through the capillary tube i. e.

$$\Delta H \cdot A = l \cdot a$$

where A is the area of the reservoirs
 a is the area of the capillary tube
 l is the linear movement of the bubble.

$$(4) \frac{\Delta H \cdot D^2}{4} = \frac{l \cdot a \cdot D^2}{4}$$

where

D is the diameter of the large reservoirs

d is the diameter of the capillary tube rearranging and substituting 4 in 3

$$P = 2l \frac{D^2}{D^2} \left(2 - \frac{\rho_p}{\rho_m} \right) + \Delta p$$

Solving for the sensitivity

$$(5) S = \frac{l}{P} = \frac{1}{2 \frac{D^2}{D^2} \left(2 - \frac{\rho_p}{\rho_m} \right)} - \frac{\Delta p}{P} \left[\frac{1}{2 \frac{D^2}{D^2} \left(2 - \frac{\rho_p}{\rho_m} \right)} \right]$$

Defining the manometer constant, C , in terms of dimensions and physical properties:

$$(6) C = \frac{1}{2 \frac{D^2}{D^2} \left(2 - \frac{\rho_p}{\rho_m} \right)}$$

Substituting in 6 the values,

$$d = 0.126 \text{ cms.}$$

$$D = 8.10 \text{ cms.}$$

$$\rho_m = 13.534 \text{ g./cc. at } 25^\circ \text{ C.}$$

$$\rho_p = 0.6213 \text{ g./cc. at } 25^\circ \text{ C.}$$

$$C = 1056$$

It will be understood that the dimensions and densities given above merely represent an example and the scope of the invention is not to be considered as limited thereto.

Substituting the constant in 5

$$S = 1056 - \frac{\Delta p}{P} \times 1056$$

30 The negligible effect of the Δp term on sensitivity can be shown by the following example:

Assume the pressure P to be measured is 50 microns and that the residual reference reservoir pressure P_2^o amounts to 10 microns. P_2^o will change according to the relation,

$$(7) P_2^o V = (P_2^o + \Delta p)(V - \Delta V)$$

where V is the original reference reservoir volume and,

40 ΔV is the change in the reference reservoir volume caused by the applied pressure P .

But,

$$\Delta V = \Delta H A$$

Substituting in 7 and rearranging

$$(8) \Delta p = \frac{P_2^o V}{V - \Delta H A} - P_2^o$$

Assuming a value for V of 100 cc. and solving

$$\Delta p = 6.43 \times 10^{-6} \text{ mm.}$$

and

$$(9) S = 1056 - 1056 \times 1.29 \times 10^{-4} = 1056 - 0.129$$

thus, less than 0.013% change in sensitivity would result from 10 microns residual pressure in upper reservoir 12. Similarly it can be shown that a reference reservoir pressure of 780 microns would be required to change the sensitivity by 1%. Hence, for all practical purposes, this factor can be disregarded and the sensitivity regarded as equal to the manometer constant.

$$S = 1056$$

therefore,

$$P = \frac{l}{1056}$$

The example here given and the particular description set forth are merely presented in order to illustrate how the invention may be applied. Other forms and variations coming within the scope of the appended claims will readily suggest themselves to those skilled in the art.

I claim:

1. A micromanometer, comprising a pair of vertically arranged U-tubes each having a long

leg and a short leg, reservoirs connected to the ends of said legs, and a capillary tube connecting the reservoirs on the short legs.

2. A micromanometer, comprising a pair of vertically arranged U-tubes each having a long leg and a short leg, reservoirs having a diameter greater than said legs connected to the ends of said legs, a capillary tube connecting the reservoirs on the short legs, and valve means connected to said capillary tube.

3. A micromanometer, comprising a pair of vertically arranged U-tubes each having a long leg and a short leg, reservoirs having a diameter greater than said legs connected to the ends of said legs, a capillary tube connecting the reservoirs on the short legs, valve means connected to said capillary tube, and means associated with the aforesaid elements to measure the pressure of a fluid introduced into said micromanometer.

4. A micromanometer, comprising a pair of vertically arranged U-tubes, each having a long leg and a short leg, reservoirs having a diameter greater than said legs connected to the ends of said legs, a capillary tube connecting the reservoirs on the short legs, valve means connected to said capillary tube, and means contained within said capillary tube to indicate the pressure of a fluid introduced into said micromanometer.

5. A micromanometer, comprising a pair of vertically arranged U-tubes each having a long leg and a short leg, reservoirs having a diameter greater than said legs connected to the ends of said legs, a capillary tube connecting the reservoirs on the short legs, valve means connected to said capillary tube, an index bubble contained within liquid in said capillary tube, and valve means associated with the reservoirs on the long legs.

6. A micromanometer, comprising a pair of vertically arranged U-tubes each having a long leg and a short leg, reservoirs having a diameter greater than said legs connected to the ends of said legs, a horizontal capillary tube connecting the upper portions of the reservoirs on the short legs, valve means connected to said capillary tube, an index bubble contained within liquid in said capillary tube, and valve means associated with the reservoirs on the long legs.

7. A micromanometer, comprising a pair of vertically arranged U-tubes each having a long leg and a short leg, reservoirs having a diameter greater than said legs connected to the ends of said legs, a horizontal capillary tube connecting the upper portions of the reservoirs on the short legs, valve means connected to said capillary tube, an index bubble contained within liquid in said capillary tube, valve means associated with the reservoirs on the long legs, a tubular element connecting said reservoirs on the long legs, and means adapted to admit fluids into one of said reservoirs on the long legs and said tubular element.

8. In a micromanometer, comprising a pair of vertically arranged U-tubes each having a long leg and a short leg, reservoirs connected to the ends of said legs, and a capillary tube connecting the reservoirs on the short legs, pressure indicating means, comprising mercury columns contained within said legs and partially filling said reservoirs, and a liquid having a relatively low viscosity and surface tension contained within said capillary tube and partially filling said reservoirs on the short legs, and an index bubble contained within the liquid in said capillary tube.

9. In a micromanometer, comprising a pair of vertically arranged U-tubes each having a long leg and a short leg, reservoirs having a diameter greater than said legs connected to the ends of said legs, and a capillary tube connecting the reservoirs on the short legs, pressure indicating means, comprising mercury columns contained within said legs and filling said reservoirs to the extent of about one half the volume thereof, a liquid having a relatively low viscosity and surface tension contained within said capillary tube and filling said reservoirs on the short legs to the extent of about one half the volume thereof, and an index bubble positioned in said liquid.

10. In a micromanometer, comprising a pair of vertically arranged U-tubes each having a long leg and a short leg, reservoirs having a diameter greater than said legs connected to the ends of said legs, and a capillary tube connecting the reservoirs on the short legs, pressure indicating means, comprising mercury columns contained within said legs and filling said reservoirs to the extent of about one half the volume thereof, normal pentane contained within said capillary tube and filling said reservoirs on the short legs to the extent of about one half the volume thereof, and an index bubble positioned in said pentane.
